UNITED STATES PATENT OFFICE.

FRANK ZALESKI, OF SOMERVILLE, MASSACHUSETTS, ASSIGNOR TO REECE SHOE MACHINERY COMPANY, OF BOSTON, MASSACHUSETTS, A CORPORATION OF MAINE.

METHOD OF FOLDING SHEET MATERIAL.

1,265,578.

Specification of Letters Patent.

Patented May 7, 1918.

Application filed March 31, 1917. Serial No. 158,860.

To all whom it may concern:

Be it known that I, FRANK ZALESKI, a subject of the Emperor of Germany, residing at Somerville, county of Middlesex, State of 5 Massachusetts, have invented an Improvement in Methods of Folding Sheet Material, of which the following description, in connection with the accompanying drawing, is a specification, like characters on the 10 drawing representing like parts.

This invention relates to a method of folding sheet material so that the folded article will present a portion of double thickness at its periphery and will be provided with an 15 upturned lip at a slight distance from its peripheral edge and at the inner boundary of the portion of double thickness. My improved method may be used for making a variety of articles where it is desired that 20 the peripheral portion of the article should be of double thickness and it is also desired that the article should present an upturned lip at a slight distance from the periphery. I have chosen to illustrate my 25 invention herein as it might be practised in producing an insole for a welt boot or shoe having the above characteristics. I desire to state, however, that the invention is not limited to the production of insoles and an 30 insole has been referred to merely as a means of illustrating the principal features of the invention.

I have shown in the drawings some of the steps of my improved process and have also 35 illustrated a machine by means of which the process may be carried out.

Figure 1 of the drawings shows the essential elements of a folding machine by which my improved process may be carried out 40 with the parts in position ready to make the fold;

Fig. 2 shows the first step in the folding operation;

Fig. 3 illustrates the final step in the 45 folding operation;

Fig. 4 is a plan view of the shape-giving element;

Fig. 5 is a plan view of the combined die and folding element;

50 Fig. 6 is an underside view of the combined die and folding element;

Fig. 7 is a view of the blank from which the insole is made;

Fig. 8 is a perspective view of the completed insole.

My improved process involves the folding of a sheet of material to produce an article which has a double thickness at its peripheral portion and has an upturned lip adjacent its periphery at the inner edge of the 60 portion of double thickness. For instance, in Fig. 8, I have shown an insole to illustrate one form of article made in accordance with my invention, and this has the body portion 40, the peripheral marginal portion 65 42 of double thickness, and the upturned lip 43 situated adjacent the inner edge of the portion 42 of double thickness. In making an article having this characteristic by my improved process, I first bend or 70 upturn a sufficient amount of the marginal portion of a blank of sheet material into a position at substantially right angles to the body thereof and then I form a fold entirely in that part of the upturned marginal 75 portion which is immediately circumjacent the portion of the sheet that has not been upturned, thereby to produce the folded marginal portion 42 of the completed article, the peripheral edge portion of the upturned marginal portion remaining in its upturned position to produce the lip 43.

When the folded marginal portion 42 of the article is completed, one of the plies of the fold occupies the plane of the portion of 85 the sheet which was not upturned.

In folding the marginal portion of the blank of sheet material into its position at substantially right angles to the body thereof, I will preferably employ a shape-giving 90 element which engages the central portion of the blank and against the sides of which the marginal portion of the blank may be upturned, and in the succeeding step of folding a part of the upturned marginal 95 portion, I will preferably use a folding member which grips the upturned marginal portion and presses it against the sides of the shape-giving element and then is moved toward the face of said shape-giving element 100 thereby carrying the upturned marginal portion toward said face and forming the outwardly-folded portion 42.

The above-described steps of the process will perhaps be better understood by reference to an apparatus such as that herein illustrated and by which the process may be practised, and I will, therefore, proceed to describe the device shown. I wish to state, however, that this apparatus has been illus- 110

trated simply to assist in giving an understanding of the process and that the steps of the process may be carried out by apparatus constructed differently from that herein shown.

In the device illustrated 1 indicates a bed, 2 indicates an element that for convenience I will term the shape-giving element, and 3 indicates generally a combined die and folding element. The combined die and folding element comprises a main or body portion 6 and a plurality of folding blades 4 and 5 which are sustained on the body portion and are movable radially. The shape-giving element 2 has a shape corresponding to the interior contour of the upturned lip 43 of the completed article. The folding blades 4 and 5 are so constructed that they present a biting edge 7 which has a similar contour, these edges being formed by making the blades with the backwardly inclined walls 8. The combined die and folding element is shown as having a pocket 9 therein immediately above the opening 10 which exists 25 between the folding blades, which pocket 9 is preferably of the size and shape to receive the blank from which the article is to be made. Where this article is an insole, such as shown in Fig. 8, the blank which is designated 11 will be of substantially the shape shown in Fig. 7. In folding this blank in accordance with my invention, said blank is first placed in the pocket 9 when the elements of the folding machine are in the relative position shown in Fig. 1. The folding blades 4 and 5 are in their retracted position so that the opening 10 between them is slightly larger than the shape-giving element 2. The shape-giving element 2 is then depressed through the opening 10, as shown 35 in Fig. 2, thus forcing the blank 11 there-through and causing the marginal portion 12 of the blank to be upturned against the sides of the shape-giving element 2. The movement of the shape-giving element 2 carries the body of the blank against the bed 1, and the folding blades 4 and 5 are so spaced relative to the bed that when the shape-giving element is in the position shown 40 in Fig. 2, the folding blades engage the upturned marginal portions 12 relatively near the peripheral edge thereof. When the parts are in this position, the blades 4 and 5 are moved inwardly so as to bring the biting or gripping edge 7 firmly against the upturned marginal portion 12. The folding element 3 is then depressed into the position shown 45 in Fig. 3, and during this operation the folded edge portion 42 of the completed article is formed from that portion of the upturned marginal portion 12 of the blank which is situated between the gripping edge 7 in Fig. 2 and the portion of the blank which has not been upturned. The gripping 50 edge 7 is pressed firmly against the upturned

sides of the blank and when the folding blades are depressed, this gripping edge 70 grips the upturned portion of the blank and forces it downwardly relative to the shape-giving element 2, and during this downward movement the part of the upfolded marginal portion 12 between the edge 7 and the bed 1 is formed into the outwardly-extending fold 42. The peripheral part 13 of the upfolded marginal portion 12 which is above the gripping edge 7 remains in contact with the side walls of the shape-giving element 2 and thus 75 forms the upturned lip 43 of the completed article. After the article is thus completed, the shape-giving element 2 and folder 3 are returned to their normal position shown in Fig. 1.

The folding elements 4 and 5 operate not only to make the fold 42, but also to set this fold. Where the surface of the bed 1 on 85 which the fold is made is a plane surface, then when the fold 42 is formed in the completed article, the under or lower ply of the fold will be formed in the plane of the body of the blank 11.

In the construction illustrated, the bed 1 is shown as having a shoulder 14 encircling the portion of the bed on which the fold is made, said shoulder having such a shape and contour as to fit the peripheral edge of 95 the fold 42. The shoulder 14 thus assists in giving the proper shape to the periphery of the completed article.

Any suitable means may be employed for giving movement to the shape-giving element 2 and the folder element 3. I have herein illustrated a shaft 15 having a cam 16 thereon which actuates a plunger 17 to which the shape-giving element 2 is secured, this cam giving the proper movement to said 100 shape-giving element. The folder 3 is given its vertical movement by means of cams 170 on the shaft 15, said cams acting against the rods 18 extending upwardly from the folder element. Springs 30 and 31 operate to hold 105 the shape-giving element and rods against the cams and thus to raise the shape-giving element and folder element at the proper time. The folding blades 4 and 5 are preferably acted upon by springs 19 which tend 110 to hold them separated from each other and they are moved inwardly into firm contact with the upfolded marginal portion 12 of the work, as shown in full lines Fig. 2, by cams 21 which are actuated by levers 22. 115 These levers are in turn actuated by wedge members 44 which are guided in the frame and which are given their operative movement by cams 45 on the driving shaft 15. The cams 45 are so timed as to move the 120 wedge members downwardly at the proper time in the cycle of operations to clamp the folding members against the upfolded portion 12.

From the above it will be seen that my im- 130

proved process involves the upturning of a marginal portion of a blank of sheet material and then forming an outwardly-extending fold entirely in that part of the upturned marginal portion which is immediately circumjacent the portion of the blank that has not been upturned. In the illustrated embodiment of the invention the outwardly-extending fold is so formed that when it is completed, one of the plies thereof occupies the plane of the body of the blank. The entire folded portion 42 of the completed article is nevertheless formed entirely from the portion of the blank which was upturned before the fold was made.

While I have illustrated herein one way in which my improved process may be carried out, I do not wish to be limited thereto.

I claim:

1. The method of folding sheet material which consists in upturning the marginal portion of a sheet and then forcing the peripheral part of the upturned portion toward that part of the sheet which is not upturned thereby to form an outwardly-extending fold in that part of the upturned marginal portion which is immediately circumjacent the portion of the sheet which has not been upturned.

2. The method of folding sheet material which consists in upturning the marginal portion of a sheet and then making an outwardly-extending fold which is formed entirely in that part of the upturned marginal portion which is immediately circumjacent the portion of the sheet which has not been upturned and retaining the peripheral part of the upturned marginal portion in its upturned position.

3. The method of folding sheet material which consists in upturning the marginal portion of a sheet and then forcing the peripheral part of said upturned portion toward that portion of the sheet which has not been upturned in the direction of the upturned portion thereby to form in said upturned portion an outwardly-extending fold.

4. The method of folding sheet material which consists in upturning the marginal portion of a sheet and then doubling on itself that part of the upturned marginal portion immediately circumjacent the portion of the sheet which is not upturned while retaining the peripheral part of said upturned marginal portion in its upturned position.

5. The method of folding sheet material which consists in upturning the marginal portion of a sheet against the sides of a shape-giving element, engaging said upturned portion along a line near its edge, and then forcing said upturned portion toward the face of said element thereby to form an outwardly-extending fold in that

part of the upturned portion which is immediately circumjacent the portion of the sheet that is not upturned.

6. The method of folding sheet material which consists in upturning the marginal portion of a sheet against the side wall of a shape-giving element, pressing said upturned portion against the side wall of said element along a line separated from the face of said element and then moving the part of the upturned portion which is thus pressed against the side wall downwardly toward the face of the element thereby to form an outwardly-extending fold in the part of the upturned portion between the face of said element and the point where said upturned portion is pressed against said wall of the element.

7. The method of folding sheet material which consists in upturning the marginal portion of a sheet, making an outwardly-extending fold which is formed entirely in that part of the upturned marginal portion which is immediately circumjacent the portion of the sheet that has not been upturned and then pressing said outwardly-extending fold.

8. The method of folding sheet material which consists in upturning the marginal portion of a sheet, forming in the upturned marginal portion an outwardly-extending fold, one ply of which occupies the plane of that portion of the sheet which has not been upturned and retaining the peripheral part of said upturned marginal portion in its upturned position while the fold is being made.

9. The method of folding sheet material which consists in upturning the marginal portion of a sheet material, engaging the marginal portion near the peripheral edge thereof and moving said peripheral edge toward that portion of the sheet which has not been upturned thereby to form an outwardly-extending fold in the part of the upturned portion between the point where it is engaged and the part of the sheet which has not been upturned.

10. The method of folding sheet material which consists in bending said sheet over the end of a shape-giving element with the marginal portion of the sheet against the side wall of said element and forcing the peripheral part of said upturned portion toward the face of said element while in contact with the side wall thereof thereby to form an outwardly-extending fold in the upturned marginal portion.

11. The method of folding sheet material which consists in upturning the marginal portion of a sheet while holding the central portion thereof in a flat condition and then folding that part of the upturned marginal portion which is immediately circumjacent the central portion of the sheet thereby to form an outwardly-extending fold, one ply

of which fold is in the plane of the central part of the sheet, and retaining the peripheral part of the upturned marginal portion in its upturned position while the fold is being made.

12. The method of folding sheet material which consists in upturning the marginal portion of a sheet against the side wall of a shape-giving element and then moving the

edge of said upturned portion toward that portion which has not been upturned and leaving the intermediate part of said upturned portion free to be formed into an outwardly-extending fold.

In testimony whereof, I have signed my name to this specification.

FRANK ZALESKI.
